UNITED STATES PATENT OFFICE

KURT WIEGAND, OF BERLIN, GERMANY, ASSIGNOR TO GENERAL ELECTRIC COMPANY,
A CORPORATION OF NEW YORK

ELECTRIC LAMP

Application filed December 2, 1925. Serial No. 72,735, and in Germany February 9, 1925.

My present invention relates to electric lamps for use with high voltage circuits and to apparatus for applying high voltage currents to the lamp. It relates further to high voltage lamps, transformers and connections therefor. It relates more particularly to vapor arc lamps adapted for use with high voltage currents and to transformers and other apparatus therefor.

10 Heretofore electric illuminating tubes and their apparatus for use on sign boards, walls or ceilings have when used on high voltage circuits presented wiring difficulties on account of safety requirements.

15 For this reason resort has been had to the use of boxes for holding the lighting tubes from the front of which the illuminating portions of the tubes extend and inside of which the electrodes, transformers and connections are arranged. It has already been proposed, with regard to sign boards to put up a special box for the holding of all parts of the different high voltage tubes, as well as to arrange in the case of freely outstanding illuminating tubes a narrow box extending under or over the tubes for holding the electrodes, transformers and connections.

20 This invention allows the arrangement in a simple manner of the wiring of illuminating tubes in accordance with prevalent safety requirements and this is a simple and economical manner. For this purpose, according to this invention, a lamp envelope terminal portion or bulb or even both bulbs or terminal portions of a single lamp, or two or more neighboring terminal portions or bulbs of different lamps are surrounded by a substantially ring shaped transformer and enclosed with the transformer in a casing or shell. If a choke coil, ohmic resistance or condenser is connected in series to the primary coil then these also can be formed in ring shape and placed inside of the casing or shell about the lamp tube terminal or bulb. Accordingly one no longer needs large boxes, often hard to attach, for the wiring of such illuminating tubes and for parts under a high tension. The cases or shells are formed as units with the electrode portions of the lamp, are hardly conspicuous and can be con-

veniently fastened. Finally, the compactness of the electrode and transformer, occasioned by the ring shape of the transformer, permits the use of very short high voltage lines and these inside of the transformer case or cases.

55 Several embodiments of electrode casings in accordance with this invention are shown in the accompanying drawing:

Fig. 1 is a vertical mid-section view through the end of a vapor arc lamp having a bulb terminal portion with an electrode therein and a lead sealed therethrough, a transformer in the shape of a ring positioned about the terminal portion of the lamp and a casing about the terminal and the transformer.

60 Fig. 2 is a transverse sectional view taken along line 2—2 of Fig. 1 and looking in the direction of the arrows.

Fig. 3 is a vertical mid-sectional view of 70 a device similar to that of Figs. 1 and 2 but in which the ring transformer is in the form of a conical frustum.

Fig. 4 is a transverse sectional view taken along the line 4—4 of Fig. 3 and looking in 75 the direction of the arrows.

Fig. 5 is a plan view with the casing taken away showing an elongated ring shaped transformer and having positioned in its central opening two lamp terminals, and 80

Fig. 6 is a vertical mid-section of a terminal portion of a gaseous vapor lamp, a choke coil and a transformer formed in the shape of rings and positioned about the terminal portion of the lamp and with a casing 85 about the choke coil, the transformer and the terminal portion of the lamp.

In the embodiment illustrated in Figs. 1 and 2 the lamp tube terminal portion or bulb *c* provided at the end of the illuminating tube *a* and having the electrode *b* therein is enclosed in a bottle like shell *d*. On the bottom of this shell is placed a ring shaped transformer *f* which surrounds said terminal portion *c*. The neck part of the shell *d* terminates at the outside in a suitable detachable end cover *g*.

90 In the embodiment illustrated in Figs. 3 and 4 the arrangement is essentially the same, but in this case the shell *d* and also the ring 95 100

shaped transformer f are made conical. In order to give the transformer a safe hold in the shell d , in case it is not fastened to the bottom e , corresponding stops h , can be provided in the shell, as indicated by the dotted lines.

5 If the primary and secondary coils of the transformer f are wound over one another, as is indicated in the embodiment of Figs. 10 1 and 2, then either a choke coil or an ohmic 15 resistance or a condenser must be connected in series to the primary according to usual practice. But it is a good plan, as shown in Fig. 4 to arrange primary coil f^1 and secondary coil f^2 opposite each other upon the core of the transformer leaving the intermediate spaces f^3 and with this arrangement of coils the transformer has a sufficient leakage so that the series connection of a choke coil and ohmic resistance or a condenser can be dispensed with.

20 In the embodiment illustrated in Fig. 5, two adjacent electrode enclosures c^1, c^2 of two tubes a^1, a^2 arranged adjacent each other are surrounded by an oval ring transformer f^4 and enclosed in a common shell d^1 . In this case also the transformer, with the simplification of the arrangement, possesses a sufficient leakage through placing the primary and secondary coils f^1, f^2 opposite each other. If the several tubes come together in a corner, then more than two electrodes can also be surrounded by a transformer carrying several coil-windings and can be built into a 35 common shell.

Finally, in a given case if the transformer is not especially regulated for leakage, as illustrated in Fig. 6, a choke coil i just as the transformer f , can be arranged like a ring 40 about the lamp terminal portion c inside of the shell d and as customary, can be connected in series to the primary coil. In this case, however, an intermediate insulating layer k is suitably arranged between the choke coil i 45 and the transformer f . In place of the choke coil i an ohmic resistance, formed in ring shape, or a ring shaped condenser could be used.

The outer form of the shell which surrounds as closely as possible all the parts depends upon the size of the transformer and the formation of the terminal portion of the lamp. This arrangement of the transformer and other parts is particularly adapted for 55 use in connection with electric lamps of the vapor arc type but is applicable to electric lamps generally.

What I claim as new and desire to secure by Letters Patent of the United States, is:

60 1. In combination, a gaseous electric discharge illuminating tube and a transformer therefor, said transformer being shaped to surround one or more of the terminal portions of the tube.

65 2. In combination, with a ring shaped

transformer, one or more gaseous electric discharge illuminating lamp terminal portions positioned within said transformer and means for connecting the lamp terminal to the transformer.

3. In combination with an electric lamp, a 70 transformer and a regulating element therefor formed as an enclosure, one or more terminal portions of the lamp being positioned in the enclosure and connected to said regulating element and said transformer.

4. In combination with an electric vapor 75 arc lamp having a terminal therefor, a transformer formed as an enclosure about said terminal and connected with the lamp.

5. In combination with an electric vapor 80 arc lamp having a terminal therefor, a transformer formed as an enclosure about said terminal and connected with the lamp, and a casing about said transformer serving to 85 securely hold the lamp to the transformer.

6. An electric illuminating tube, with a 90 transformer, characterized by the fact that an electrode enclosure c is surrounded by a ring shaped transformer f and enclosed together with it in a shell d .

7. An electric illuminating tube, according to claim 6, characterized by the fact that in the shell d , enveloping the electrode enclosure and the ring shaped transformer, a 95 current regulating device is arranged surrounding the electrode enclosure.

In witness whereof, I have hereunto set my hand this 13th day of November, 1925.
